UNITED STATES PATENT OFFICE.

RICHARD J. SAVAGE AND CHARLES E. SCHULTZ, OF CHICAGO, ILLINOIS.

CANDY-MAKING MACHINE.

1,162,811.

Specification of Letters Patent.

Patented Dec. 7, 1915.

Application filed February 8, 1915. Serial No. 6,416.

To all whom it may concern:

Be it known that we, RICHARD J. SAVAGE and CHARLES E. SCHULTZ, both citizens of the United States, residing at Chicago, Illinois, have invented certain new and useful Improvements in Candy-Making Machines, of which the following is a specification.

The primary object of this invention is to provide certain improvements upon the candy-making machine shown and described in our prior United States patent, dated October 8, 1912, No. 1,040,427, reissued December 1, 1914 as No. 13,836. In the machine described and shown in our aforesaid prior patent, the vertical shaft which carries the dasher by which the stirring of the contents of the kettle is effected must be lifted out of the kettle by means of a block and tackle or pulley arrangement or some similar apparatus. In view of the fact that these machines, in actual practice, are usually at least eight feet in height and require a clearance of three or four feet for lifting the dasher shaft out of the kettle, it has been difficult to use these machines in rooms where the ceilings are low, and it is the primary object of this invention to provide a machine which, although possessing all of the salient features of our aforesaid former machine, can also be employed in rooms with low ceilings or under other circumstances where economy of space is a necessity.

In the drawings, Figure 1 is a side elevation of the machine; Fig. 2 is a view at right angles to Fig. 1 looking toward the left in said figure; Fig. 3 is a view at right angles to Fig. 1 looking toward the right in said figure; and Fig. 4 is a view looking downwardly from above.

The base 1 is adapted to rest upon the floor, and to said base the post or column 2 is suitably bolted. An arm 4, provided with a perforated head 5 receives the rotating shaft 7, which shaft bears the miter gear 16 at its upper end. Gear 16 meshes with and is driven by a corresponding gear 15 on one end of the shaft 11. The kettle 23 is supported by a suitable yoke or wishbone 25 to which the handles 24 are secured. The rotating shaft 7 carries the dasher 43 at its lower end, which said dasher is of a shape conforming generally to the shape of the kettle 23 and is adapted to stir and agitate the contents of the kettle. The furnace 38 is adapted to burn any suitable fuel and all

other parts shown in the drawings and designated therein by reference numerals 1 to 50, inclusive, are identical in function with the correspondingly numbered parts of our said prior patent, and the construction and operation of said parts is fully described in said patent. In said prior patent, the post 2 and arms 8 and 4 are integrally united together, and the arm 4 is immovable with respect to the column or post 2. The salient feature of this invention, however, resides in the fact that the bottom part of the post 2, which engages the floor, is permanent and fixed in position, whereas the upper part 60 of the post or column, being that part with which the arms 4 and 8 are connected, is pivoted to the base or bottom of the post, and in this manner the parts at the top of Fig. 1 are permitted to swing from full line 65 position to dotted line position, as shown in said figure. The joint 51 separates the fixed part of the post 2 from the movable part, which movable part, for convenience, is designated 52 in the drawings. An ear 53 is 70 pivoted at 54 to the corresponding ear 55, the ear 53 being integrally united with the movable part of the column, and the ear 55 with the immovable part thereof. Secured to the movable part 52 is the platform or 75 shelf 56 upon which the motor 14 is adapted to rest, the revolution of the motor being translated into rotation of the shaft 7 by means of the transmission gears 12 and 13, shaft 11, and miter gears 15 and 16. All of 80 these parts in an obvious manner are adapted to be tilted from full line position, Fig. 1, to the dotted line position in the same figure, and this rocking movement of the dasher and the means for driving the same 85 is accomplished simultaneously as the kettle 23 is elevated. As explained in our said prior patent, removal of the candy from the fire is often necessary, and it is often desirable to permit the candy to cook until the 90 very instant that it begins to boil, then to stop the cooking and to lift the kettle and its contents away from the heat. In the machine depicted in our said prior patent, this desired end is accomplished by mechanism which simultaneously elevates the kettle and the dasher shaft, but as previously explained herein, such a machine requires a block and tackle or pulley arrangement for elevating the dasher shaft clear of the kettle. In this invention, by rocking the parts 95 from full line position to dotted line posi-

tion, the dasher and associated parts are carried clear of the kettle and yet at the same time are not very much higher above the floor than they are when the machine is in operation.

- 5 In order to permit the movement of the dasher and associated parts the lever 57 is provided, being journaled in ears 58, which are formed upon the fixed part or column 2. 10 A crank-arm 59 is connected to said lever, and the pitman 60 extends from the end of the crank arm 59 to the shelf 56, being connected to said shelf 56 by the pin 61 which passes through the ears 62 and through the 15 upper end of the pitman 60. Said ears 62 are formed integral with the shelf 56 or otherwise firmly and permanently united thereto. At its lower end, the pitman 60 is connected by a pin 63 to the crank arm 59. 20 When the lever 57 is rocked in a clockwise direction, the movements of the crank arm and pitman 69 in an obvious manner translate the rocking of the lever 57 into movement of all of the parts which are carried 25 upon the pivotal connection 54.

The wishbone or yoke 25 comprises two arms suitably connected together to form a base 66, which base is perforated so as to receive the fixed guides or rods 67 upon which 30 guides the base is adapted to rise and fall. A link 68 is pivoted at 69 to the base 66, and is also pivoted at 70 to the rocking table 56; hence, as the table 56 and associated parts are moved from full line position to 35 dotted line position under the action of the lever 57, the link 58 causes the wishbone 25 and the kettle 23 to move vertically toward or away from the fire, and in this manner the single operation of rocking the lever 57 40 simultaneously elevates the kettle and causes the dasher 43 and all of the other parts which are in connection with the rocking table 56 to be lifted away from the kettle. The rotation of the dasher shaft 7 and 45 dasher 43 is not stopped because the parts are moved to the dotted line position, Fig. 1, but the dasher and dasher shaft may continue to rotate even after they have been lifted entirely or partly out of the kettle 23.

50 We claim as our invention:

1. A candy-making machine comprising a kettle, a dasher shaft projecting thereinto, a heater, a slidably mounted yoke adapted to support the kettle above the heater, means 55 supporting said dasher shaft, said supporting means being pivotally mounted, and means for causing said supporting means to rock upon the pivotal support provided therefor.

60 2. A candy-making machine comprising a kettle, a heater, a slidably-mounted yoke adapted to support the kettle above the heater, a dasher shaft projecting into the kettle, means for supporting said shaft, said 65 supporting means being pivotally mounted,

means for causing said support to rock upon the pivot provided therefor, and means to elevate the kettle support, the two means last-mentioned being adapted to be operated from a single source of power.

70

3. A candy-making machine comprising a kettle, a dasher shaft projecting thereinto, a heater, a slidably-mounted yoke adapted to support the kettle above the heater, means within which said dasher shaft is adapted to revolve, and means for causing said shaft-holding means to travel in the arc of a circle and out of the way of said kettle.

75

4. A candy-making machine comprising a kettle, a dasher shaft projecting thereinto, a heater, a column adapted to be fixed permanently in position, a yoke adapted to support the kettle above the heater and slidably-mounted upon said column, means for holding said dasher shaft within which said shaft is adapted to revolve, said shaft-holding means being pivotally mounted upon said column, and means for causing said shaft-holding means to rock upon the pivot provided therefor, there being a connection 85 between the kettle-supporting yoke and said shaft-holding means whereby actuation of the one produces actuation of the other.

90

5. A candy-making machine comprising a kettle, a dasher shaft projecting thereinto, a heater, a column adapted to be fixed permanently in position, a yoke adapted to support the kettle above the heater and slidably mounted upon said column, a dasher shaft projecting into the kettle, an arm within 100 which said shaft is journaled, said arm being in pivotal relation with said fixed column, a motor in fixed relation with said arm, means intermediate said motor and said shaft adapted to cause said motor to drive said shaft, a lever, and means intermediate said lever and said pivoted arm whereby the rocking of said lever causes 105 rocking of said arm.

100

6. A candy-making machine comprising a 110 kettle, a dasher shaft projecting thereinto, a heater, a column adapted to be fixed permanently in position, a yoke adapted to support the kettle above the heater and slidably mounted upon said column, a dasher shaft 115 projecting into the kettle, an arm within which said shaft is journaled, said arm being in pivotal relation with said fixed column, a motor in fixed relation with said arm, means intermediate said motor and 120 said shaft adapted to cause said motor to drive said shaft, a lever, and means intermediate said lever and said yoke adapted to translate the rocking of said lever into vertical reciprocation of said yoke.

125

7. A candy-making machine comprising a kettle, a dasher shaft projecting thereinto, a heater, a column adapted to be fixed permanently in position, a yoke adapted to support the kettle above the heater and slidably 130

mounted upon said column, a dasher shaft projecting into the kettle, an arm within which said shaft is journaled, said arm being in pivotal relation with said fixed column, a motor in fixed relation with said arm, means intermediate said motor and said shaft adapted to cause said motor to drive said shaft, a lever, and means intermediate said lever and said arm adapted to translate the rocking of said lever into rocking of said arm, and other means intermediate said

arm and said yoke adapted to translate the rocking of said lever and of said arm into vertical reciprocation of said yoke.

In testimony whereof we have hereunto affixed our names in the presence of two witnesses.
